(57) **CLAIM**

The ornamental design for a boat deck bow portion with integral wedge as shown and described.

DESCRIPTION

FIG. 1 is a front left perspective view showing the boat deck bow portion with integral wedge of Applicants' invention. FIG. 2 is a back right perspective view of the boat deck bow portion with integral wedge of FIG. 1.

FIG. 3 is a front elevation view of the boat deck bow portion with integral wedge of FIG. 1.

FIG. 4 is back elevation view of the boat deck bow portion with integral wedge of FIG. 1.

FIG. 5 is top plan view of the boat deck bow portion with integral wedge of FIG. 1.

FIG. 6 is a left side elevation view of the boat deck bow portion with integral wedge of FIG. 1.

FIG. 7 is a right side elevation view of the boat deck bow portion with integral wedge of FIG. 1; and,

FIG. 8 is a right side elevation view showing the boat deck bow portion with integral wedge in conjunction of a trolling motor.

The dash-dot-dash broken lines illustrate the boundaries of the claimed design.

The dash-dash broken lines represent the environment in which the article resides and forms no part of the claimed design.

1 Claim, 6 Drawing Sheets
